PNEUMATIC FIREMAN'S TOOL FOR BREAKING
GLASS BLOCKS AND OTHER WALL BUILDING
MATERIALS

Harold E. Roeder, 6 Churchill Lane, Lexington, Mass.

Filed July 27, 1960, Ser. No. 45,675

3 Claims. (Cl. 125—40)

This invention relates to an improved percussion type fire fighting apparatus, and more particularly to a pneumatically operated percussion head for use in breaking through a side wall of a burning building in order to provide a suitable air vent.

Difficulty is presently experienced by firemen in dealing with side wall structures of buildings constructed from so-called "Glass Blocks." These blocks are extremely resistant to penetration by firemen's axes and even conventional forms of percussive tools. It is further difficult to enlarge a small opening to a required size in order to provide quickly a sufficiently large venting aperture.

It is a chief object of the present invention to provide an improved firemen's tool and to devise a pneumatically actuated type of block piercing member for use in venting building sidewalls of glass block construction as well as other structures.

A still further object is to provide a special percussion head which combines a piercing tip with a plurality of impact surfaces capable of smashing through glass blocks and rapidly enlarging a small entering opening.

Another object of the invention is to provide a block breaking tool which can be conveniently attached to and operated with conventional types of air hammers and similar devices.

Still another object is to devise a breaking tool having novel hand guard means provided therein.

The nature of the invention and its other objects and novel features will be more fully understood and appreciated from the following description of a preferred embodiment of the invention selected for purposes of illustration and shown in the accompanying drawings, in which:

FIG. 1 is a diagrammatic view illustrating fragmentarily sidewall construction and further indicating the block breaking tool of the invention in an operative position;

FIG. 2 is a side elevational view showing the several component parts of the block breaking tool detached from the air hammer member indicated in FIG. 1;

FIG. 3 is a front elevational view of the head of the block breaking tool; and

FIG. 4 is a cross section taken on the line 4—4 of FIG. 3.

In accordance with the invention I have devised a novel combination of pneumatic hammer and glass smashing tool which includes an elongated shaft, a percussive head having a piercing tip, and a series of impact surfaces occurring in specially stepped relationship to the piercing tip. These impact surfaces are arranged in a position to progressively smash and break out sections of glass block material of the type commonly used in sidewalls of glass block construction. A further important feature of the tool is a plurality of conical surfaces which are separated from one another by V-shaped grooves. These conical surfaces are designed to exert a unique reaming action in conjunction with hammer blows. To augment the hammering action of the impact surfaces, I further provide a plurality of radially disposed hammer bars located in spaced-apart relationship to one another.

Considering this structure in greater detail, numeral 2

2

denotes an elongated body portion. This elongated body portion 2, as shown in FIG. 2, is formed at one end with a reduced shank 4 adapted to engage in a suitable chuck mechanism, or other holding device for a pneumatic hammer, for example.

In FIG. 1, I have illustrated a pneumatic hammer of conventional construction which operates to reciprocate the percussion head of the invention at a relatively high rate of speed, and thus provides for delivering a series of hammer blows against the surface of a glass wall. The pneumatic hammer is indicated by the numeral 6 in FIG. 1 and the elongated body portion 2 is shown supported by an operator in a horizontally disposed position and engaging against a wall W composed of glass blocks as B, B1, B2, etc.

As illustrated in FIGS. 2 and 4, the percussion head, generally indicated by reference character H, is rigidly mounted on an extremity 2a of body portion 2 which extends through a centrally located opening 3, as best shown in FIG. 4. The percussion head H is formed with a rear flat surface 10 which is designed to abut solidly against an annular shoulder 12 formed on the elongated body portion 2, as suggested in FIG. 4.

The percussion head H comprises an annular part 5 which is further formed with a forwardly extending conical section 7 (FIG. 4). At the front of the conical section 7 is solidly fitted a piercing tip 9, also of conical form, as indicated in FIGS. 3 and 4.

In accordance with the invention I provide a series 30 of impact surfaces which occur in successively stepped relationship on the conical piercing tip 9; also on the conical section 7, and also on the annular part 5. These impact surfaces are further arranged such that each surface lies adjacent to a conical reaming surface. By 35 means of this arrangement alternate reaming and hammering are successively carried out to first pierce, and then progressively smash out portions of the glass blocks as suggested by blocks B2 and B3 in FIG. 1, and thus provide desired vents.

As may be more clearly seen from an inspection of FIGS. 2 and 4, the tip 9 comprises a first conical surface S which is recessed to provide a cylindrical part C, an impact surface S1, another conical surface S2, and a cylindrical part C1.

Likewise, the member 7 is formed to provide a cylindrical part C2 of the same diameter as part C1, an impact surface S3 and a conical surface S4. The surface S4 is further interrupted by a plurality of V-grooves as 15, 17 and 19. Immediately adjacent to the interrupted conical surface S4 are located a plurality of hammer bars 20, 22, 24, etc., which are fitted into the annular part 5 of the head to provide a series of spaced-apart radially disposed members as shown in FIG. 3.

In operation a fireman may assume a position, as 55 shown in FIG. 1, with the elongated body portion 2 held in the left hand which is protected by means of a circular guard G secured at an intermediate portion of the member 2 as illustrated in FIGS. 1, 2 and 3. With the pneumatic hammer 6 reciprocated from a portable source of 60 compressed air carried by the operator, the percussion head is firmly held against the surface of a glass block such as the block B of FIG. 1, and the conical piercing tip 9 engages in the block and starts to form a small opening. The conical surface S of the piercing tip immediately enlarges the pierced hole throughout a small section of the glass block. The edges of the hole thus started are almost immediately subjected to a hammering action from the small impact surface S1 which tends to smash and break away small portions of the glass block 65 in an effective manner. This provides for a further enlarging and reaming action to be carried out by the conical surface S2. Similarly, the second impact surface S3

then comes into contact with the constantly enlarging hole and immediately starts to smash and break away additional portions of the glass block material.

At this stage of hole piercing a substantial diameter of opening is realized and a special type of reaming is accomplished by means of the interrupted surface S4 and its V-grooves. The V-grooves operate to cut into the glass block material forming notches which tend to induce lines of cracking and breaking in the glass block material radiating outwardly in all directions. As the full diameter of the conical surface S4 is worked into the glass block material, the hammer elements 20 finally begin to strike against the partially broken and cracked material and thereafter relatively large chunks of material may be smashed out and dislodged, as suggested in FIG. 1.

I have found that by carrying out the glass smashing operation with progressive steps of impact and reaming occurring in alternating succession, as described above, I am enabled to avoid jamming and clogging of the tool which tends to take place if the specific combination of working surfaces are not employed. As rapidity of breaking through the glass wall to obtain desired venting is highly important from a fire fighting standpoint, any jamming or clogging is highly objectionable and the tool of the invention has been found to completely overcome such a problem.

It is intended that the tool may also be used in breaking through various other structures, either in connection with fire fighting, or in other operations.

From the foregoing description, it will be apparent that I have disclosed a novel fire fighting tool which may be conveniently combined with a standard form of pneumatic hammer held by a fireman in a position to rapidly obtain the desired venting results.

While I have shown a preferred embodiment of the invention, it will be understood that various changes and modifications may be resorted to in keeping with the scope of the appended claims.

1. A fireman's tool for breaking through a building

wall of the type constructed from glass block material, said tool comprising in combination an elongated shaft, pneumatic means for reciprocating said shaft, a percussion head mounted at one end of the shaft, said percussion head including a tapered broaching tip for piercing a hole in the glass block material, a plurality of conical reaming surfaces located rearwardly of the tip and extending outwardly in a radially increasing dimension to enlarge the size of the hole, each of said conical reaming surfaces being separated from one another by annular shouldered portions projecting outwardly at right angles to the axis of the shaft to provide a series of impact surfaces of progressively larger radial dimension whereby the breaking forces may be exerted against both edges of the hole and exposed outer surfaces of glass block material immediately surrounding the hole.

2. A structure as defined in claim 1 in which the conical reaming surfaces are formed with grooves occurring in spaced apart relation to define cutting edges.

3. A structure as defined in claim 1 including a plurality of radially disposed hammer bars located in spaced apart relation around the base of the percussion head.
